UNITED STATES PATENT OFFICE

ERNST HJALMAR WALODDI WEIBULL, OF SALTSJOBADEN, SWEDEN, ASSIGNOR TO
AKTIEBOLAGET NORDISKA ARMATURFABRIKerna, OF STOCKHOLM, SWEDEN, A
LIMITED COMPANY

HAMMERING TOOL

Application filed January 14, 1928, Serial No. 246,902, and in Sweden November 28, 1927.

The present invention relates to striking or hammering tools which comprise a rotating and reciprocating striking part and a non-striking guiding part cooperating with the former part and which may or may not rotate, the striking part coacting with a suitable anvil.

In such tools it is already known how to effect, at the backward movement of the striking or hammering part, a storing of the whole or a part of the energy necessary for the forward movement (the power stroke) of the said part. Springs are commonly used for this purpose, and it has also been proposed to effect the storage of energy by compression or rarefaction by the hammering body of the air located in front of or behind the hammering body.

Both these arrangements present certain disadvantages in practice which are not found in the arrangement according to the invention, the tool according thereto being characterized by the provision of centrifugally governed bodies adapted during the backward movement of the striking part from the anvil to be displaced in opposition to the action of centrifugal force by guiding faces, the disposition of said guiding faces being such that, after the end of the backward movement, the striking part is urged towards the anvil through the intermediary of the centrifugal bodies co-operating with said faces.

Other features characteristic of the invention will be described later in connection with the embodiments of the invention shown in the annexed drawings. The tool to which the invention has been applied by way of example is of the kind in which the backward movement of the striking or hammering body is effected by co-operation between one or more oblique or curved faces or the like, arranged on the striking body or the anvil, i. e. a tool constructed in accordance with the arrangement disclosed in patent specification No. 282,641.

Fig. 1 illustrates one embodiment, and Fig. 1a a second embodiment of a tool according to the invention, in diagrammatic longitudinal section. Fig. 2 shows the rear part of

another working position of the parts of the first embodiment.

Figs. 3, 4 and 5 show other embodiments of a tool according to the invention, in diagrammatic longitudinal sections. 55

Figs. 6 and 7 show a further embodiment, in longitudinal section and in cross-section, along the line VII—VII Fig. 6 respectively, and Fig. 8 finally illustrates a seventh embodiment, likewise in longitudinal section. 60 Figs. 9 and 10 illustrate two power-diagrams. Fig. 11 is a longitudinal section of a complete tool showing one embodiment of the invention.

In all of these figures, 1 is the striking part, 2 the guiding part, 3 the anvil and 4 and 5 the oblique faces arranged on the striking part 1 and the anvil 3 and adapted to return the striking part after the power stroke. 65

Referring to the embodiment according to Fig. 1, the rear part 6 of the part 1 is provided with radial grooves 7, in which balls 8 are arranged to move. The guiding part 2 is adapted to rotate in a frame 9 and is driven by an electric motor or the like. The guiding part 2 and the striking part 1 are keyed to each other by means of tongues and grooves 10, 11 in such a way that the striking part is forced to partake in the rotation of the guiding part, although it may, at the same time, perform a reciprocating movement relatively thereto. The groove 11 may be straight, or curved, or spiral-shaped in order to allow a shockless run of the striking body in the guiding part. The rear part 80 of the guiding shell 2 is provided with inclined guiding faces 12 adapted to force the balls 8 toward the center of rotation on the recoil of the striking member. 85

Referring to the embodiment according to Fig. 1a, the balls 8 replace the tongue 10, as they run in a groove 13 arranged in the guiding part, said groove also having the same purpose as the guiding face 12. 90

The arrangement works in the following way. 95

On the part 1 striking against the anvil 3 the energy of this stroke is transmitted to the anvil and the tool fixed therein, for instance a borer, chisel, riveting tool or the 100

like. On the transmission of said stroke to the anvil, which may slide but not rotate, the striking body is subjected, by the co-operation of the oblique faces 4 and 5 and the rapid rotation of the striking body, to a power component having a backward direction and returning the striking body. During backward or recoil movement of the striking body, the balls 8 are moved inwardly by the faces 12 and, due to the effect of centrifugal force, the balls oppose and eventually arrest the recoil movement of the striking body. Following the arrest of the recoil movement of the striking body, the balls 8 rapidly revolving with the guide part 2 and striking body bear on the inclined guiding faces 12 and due to centrifugal force they produce the following striking movement of the striking body.

20 In the embodiments shown in Figs. 1 and 1a the guiding faces 12, 13 merge into a cylindrical face owing to which, if the recoil movement of the striking body is so large that the balls reach this cylindrical face, said balls no longer tend to effect the axial movement of the striking body toward the anvil. However, axial movement of the striking body, under this circumstance, may be initiated by so disposing the tool that the striking body is caused to fall by gravity to a point where the balls 8 engage the inclined faces 12.

25 Referring to the embodiment shown in Fig. 3, the face 12, forwardly merges into an oblique or curved face 16 inclined in an opposite direction. From the above it will clearly appear that a face 16 arranged in this manner will produce a power component, acting upon the striking or hammering body in a direction opposite to, but parallel with the striking movement and will thus have a braking action upon it, if the striking body should get the opportunity of advancing so far that the balls run upon said oblique face 16. This arrangement is adapted to be used when the striking tool runs idle and thus protect the striking tool from being crushed.

The embodiment according to Fig. 4 shows a second shape of the guiding face 12, 16. In this case there is also a cylindrical guiding face 15 at the rear end and between this face 15 and the guiding face 12 there is an oblique guiding face 17 which prevents the balls 8 from being unintentionally transported from the face 15 to the face 12. To carry out this transportation a pin 18 or the like operable from outside may for instance be used.

Fig. 5 shows another embodiment of the support used for the centrifugal bodies 8; these bodies, which may consist of balls, rollers or the like, are arranged to rotate in the ends of projections 19 or the like mounted so as to turn on the striking body 1.

The arrangement is otherwise analogous to the embodiment according to Fig. 3, although

the oblique faces 12, 16 are formed in a somewhat different manner.

In the embodiment according to Figs. 6 and 7 the oblique faces 12 have, as shown, a considerable inclination so that the balls 8 may be given a large radial displacement, to enable a relatively large energy storage to be made with a small axial movement of the striking body.

Fig. 8 shows a modification of the embodiment according to Fig. 3, the guiding part 2 supporting, in this case, the radially movable balls 8, which are supported in radial grooves arranged in a boss 20 projecting from the rear end of the guiding part. The arrangement, of course, presumes that the guiding part rotates.

Figs. 9 and 10 show a force and space diagram illustrating the mutual relations of the amount of the centrifugal force and the above power component, the force of translation, in the embodiments according to Figs. 3 and 4. In the diagrams the forces are supposed to be indicated along the ordinates, distances along the abscissæ, and the points *c*, *a*, *b*, *d*, *e* and *C*, *A*, *B*, *D*, *E*, respectively in Figs. 9 and 10 correspond to corresponding points in Figs. 3 and 4. The hatched areas below the datum lines *S* represent the braking-energy absorbed by the centrifugal bodies at the forward motion of the striking body, passing that point at which the stroke shall normally be transmitted to the anvil and this energy should, if an effective protection is to be obtained, be as great as the striking energy transmitted previously to the striking body which energy is, in the diagram, indicated by the shaded area above the datum lines.

A complete tool is shown in Fig. 11 in which the electric motor is connected with and drives the guiding part 2, the latter being of the form shown in Fig. 1a. The motor is located in the frame 9, as will be understood.

Having now particularly described the nature of my invention and the manner of its operation, what I claim is:

1. In a striking or hammering tool, a striking member, an anvil engageable by the striking member, said striking member being mounted for rotary and reciprocating movement, means acting on the striking member in response to centrifugal force developed incident to rotation thereof to effect striking movement of the striking member, and means acting in response to the impact of the striking member upon the anvil to effect a recoil movement of the striking member.

2. In a striking or hammering tool, a rotary drive shaft, an anvil, a striking body interposed in an axial direction between the shaft and anvil and adapted to engage the latter, means mounting said striking member for reciprocation, and for imparting the rotary movement of the drive shaft thereto, means coacting with said mounting means

and acting in response to centrifugal force developed incident to rotation of the striking member to effect striking movement of the latter, and means acting incident to the impact of the striking member on the anvil to effect recoil movement of the striking member.
